CASE FOR MOTOR UNITS

Ivar Jepson, Oak Park, Ill., assignor to Sunbeam Corporation, Chicago, Ill., a corporation of Illinois

Application October 29, 1947, Serial No. 782,762

5 Claims. (Cl. 172—36)

1

This invention relates to a case or a housing for a motor and an associated driven unit and more particularly to a case for a motor and a driven unit utilized in an electric shaver.

An object of the invention is to provide an improved case of the above character which is formed by separable parts, which is easy to manufacture, which is rugged, which can be readily assembled and which is relatively inexpensive to manufacture.

Another object of the invention is to provide a case of the above character formed by separable parts with novel means for preventing the entrance of dirt and the like to the interior of the case along the joints formed between the respective parts which at the same time gives the case a smooth exterior surface and which presents a neat and attractive appearance.

Another object of the invention is the provision in a case of the above character utilizing a shield to prevent the entrance of dirt and the like to the housing with novel means for securing the shield in position.

Another object of the invention is the provision in a case of the above character for securing a motor unit therein so that a minimum number of securing means are exposed on the exterior of the case.

Another object of the invention is the provision in a case of the above character wherein the respective parts forming the case and the motor can be positively secured together in a tightly assembled relation.

Other objects and advantages of the invention will become apparent from the following detailed description taken in connection with the accompanying drawings, in which—

Figure 1 is an elevational view of one of the parts used in a case embodying my invention;

Fig. 2 is an elevational view of another part used in the case embodying my invention;

Fig. 3 is an elevational view of one of the parts and the motor unit in an assembled relation;

Fig. 4 is an edge view of the case similar to Fig. 3;

Fig. 5 is an edge view of the case showing the respective parts thereof in position to form a unitary case;

Fig. 6 is a view similar to Fig. 5 with a shield in position on the case;

Fig. 7 is a sectional view taken substantially along the line 7—7 of Fig. 6;

Fig. 8 is a sectional view taken substantially along the line 8—8 of Fig. 6, and

2

Fig. 9 is a view of the shield showing the details of construction of a portion thereof.

My invention is concerned with a housing for enclosing the components of an electric razor, small hand power tool, or the like. For purposes of illustration, my housing is shown in the form of a case 11 for an electric shaver of the type used in shaving beards and removing hair from other parts of the body. As shown in the drawings (see Fig. 3) the case 11 is shaped to enclose a motor 13 arranged to drive a cutter (not shown) supported by spaced cutter supports 14. The latter are rigidly mounted on a shaft 16 rotatably supported in the head 17 which is secured herein to a motor bearing support block 18. The motor 13 is interconnected with the shaft 16 by means (not shown) mounted in the head 17 to effect oscillatory movement of the cutter.

One phase of my invention is directed to constructing the case 11 so that the respective components encased therein can be quickly assembled and at the same time provide an assembly in which the respective parts are securely held in position. To this end I form the case 11 in two parts, 19 and 21 (see Figures 1 and 2) shaped to fit together to form the unitary case 11 shown in Figs. 5 and 6 which is securely fastened to the enclosed components. Each part 19 and 21 is preshaped and is formed with edge portions 22 and 23, respectively, flattened at their outer extremities and integral with central portions 24 and 26 respectively. The parts 19 and 21 are so shaped that when in the assembled relation the flattened outer extremities of respective edge portions 22 and 23 on the respective parts 19 and 21 abut each other along a joint 27 on each side of the case 11. As best shown in Figures 1 and 2 each part 19 and 21 is formed with a recess 28 for receiving a portion of the motor 13 and a recess 29 which is a continuation of the recess 28 for receiving a portion of the head 17. The general shape of the recesses 28 and 29 may vary considerably. For example, as shown in Fig. 3, the cross section of the motor 13 comprising a field structure 31 and associated field coils 32 is relatively flat and relatively wide and as a consequence is wider and thicker (see Figs. 3 and 4) than the bearing blocks 18 and 33 on either end of the field structure 31. Thus, it is to be understood that the shape of the recesses 28 and 29 in each instance depends upon the particular shape of the motor 13 and the driven unit 17. Preferably the shape of the recesses is such that when the parts 19 and 21 are assembled, a cham-

ber 34 is formed on the interior of the case 11 of substantially the same configuration as the motor 13 and the head 17. There should be only sufficient clearance between the exterior of the motor 13 and the case 11 to permit mass production of the respective parts and ease of assembly.

While any desired means may be utilized for securing the case parts 19 and 21 together to form the unitary housing, I prefer to secure the respective parts 19 and 21 to the motor 13 and associated head 17 so as to form a mechanically rigid unit. Thus, as shown in Figs. 3 and 4 at one end of the case 11 I secure each part 19 and 21 to the head 17 by screws 36 disposed on opposite edges of the head 17. At the opposite end of the case 11 I secure the part 19 to the motor by screws 37 extending through the bearing block 33 at spaced positions and threaded into sleeves 38 formed in bosses 39 integral with the part 19; and secure the part 21 to the motor 13 by a screw 40 (see Fig. 6) accessible from the exterior of the case 11 extending through the part 21 and threaded into the bearing block 33. It will be noted that the screws 37 are accessible only when the part 21 is removed. It is to be understood that any other type of threaded connection for example, a stud and associated nut or the like could be used in lieu of the screws shown herein.

Any suitable means may be provided for covering the joints 27 between the abutting parts 19 and 21 to prevent the entrance of foreign material such as dirt, hair clippings and the like to the motor chamber 34. Herein, I contemplate the use of separable shields 41 (see Fig. 6) shaped to overlie portions of the respective parts 19 and 21 to cover the joints 27. Herein each shield 41 is formed in two integral portions, i. e., an enlarged portion 42 shaped to cover the exposed heads of the screws 36 securing the parts 19 and 21 respectively to the head 17 and a narrowed portion 43 extending from the head end of the case 11 to the opposite end of the case 11. Preferably in a case of this type which is held in an operator's hand, it is desirable to have a smooth exterior surface. For this purpose the enlarged end 42 is shaped to conform to the configuration of the head end of the electric razor 12. Herein the enlarged end 42 is formed with side portions 43 shaped to engage the shoulders 44 formed on the exterior of the case 11 for positioning the shield 41. The rearward edges 46 of the shield 41 engage shoulders 47. The latter shoulders are of such depth that the rearward edges 46 are substantially flush with and of the same configuration as the edge portions of the case 11. On each edge of the case the narrowed portion 43 is received in a groove 48 overlying and in communication with the joint 27. The groove is formed herein by preshaping each of the parts 19 and 21. The groove is of such depth that the narrowed portion 43 of the shield 41 when disposed therein is substantially flush with the edge surface of the case 11.

Means is provided for securing the shield in position. In this embodiment of the invention the shield 41 is secured to the case 11 at two points. Thus, as shown in Fig. 7 the enlarged end 42 of the shield 41 is formed with a bracket 49 (see Figs. 7 and 9) shaped to interfit with a clip 51 secured to the exterior of the case 11 to secure one end of a shield 41 in position. As shown the bracket 49 is formed by securing a member having a generally U-shaped cross section to the side of the shield 41 facing the case 75

11. The member is positioned on the shield such that when the latter is in position, a member 50 on the bracket 49 engages the clip 51 and stresses the latter thereby assuring a tight assembly of the respective components.

5 The clip 51 herein is in the form of an inverted T-shaped member comprising arms 52 integrally connected to a central portion or tongue 53. Each of the arms 52 is secured to the case 11 as by the 10 screws 36 extending through openings 55 formed in the respective arms. The central portion 53 is fashioned so as to be in spaced relation with the case 11 when the screws 36 are tightened. At its extreme outer end the central portion 53 is flared outwardly slightly away from the housing as shown in Fig. 7 to facilitate engagement of the member 50 with the tongue 53.

As shown in Fig. 8 the narrow portion 43 is 20 secured to the case 11 at the end thereof opposite the head 17. In this instance the extreme outer end 54 (see Fig. 8) of the narrow portion 43 is turned back on itself to form a hook that 25 engages a shoulder 56 formed on the case 11 adjacent an opening 57. The latter is formed in the case 11 for the reception of an attachment plug (not shown) utilized to conduct power to terminals 58.

30 The manner of assembling the respective components may be understood from the foregoing but is briefly summarized as follows. The part 19 and the motor unit 13 including the head 17 are assembled as shown in Figs. 3 and 4. The clips 51 are positioned as shown and screws 36 are threaded into the respective openings formed 35 in the head 17. Subsequently, the screws 37 are threaded into the sleeves 38. At this point in the assembly the part 19 and the motor unit are rigidly secured together. The part 21 is then brought into position as shown in Fig. 5. The 40 screws 36 for part 21 are threaded into the housing 17. This fixes the clip 51 and the head end of the part 21 to the motor unit. The screw 40 is thereafter threaded into the bearing block 33 from the exterior of the case 11. The shield 41 is then positioned so that the bracket 49 engages the clip 51 and the edges 43 of the enlarged portion 42 of the shield 41 engages the respective shoulders 44 and 47 formed on the case 11. The narrow portion 43 of the shield is then positioned 45 in the groove 48 and the extreme outer end 54 of the narrow portion is deformed to engage the shoulder 56.

50 The case contemplated herein may assume many shapes and forms, and while I have shown one embodiment of my invention, it will be understood that I do not wish to be limited thereto since many modifications may be made and I therefore contemplate by the appended claims to cover any such modifications as fall within the true spirit and scope of my invention.

I claim:

1. In combination, a case for a motor unit comprising two separable parts each having spaced edge portions, the edge portions of one part being 65 shaped to substantially match the edge portions of the other part when the parts are positioned to form a unitary case, each of said parts being formed with a recess of the same general configuration as a portion of said motor unit so that when the parts are assembled a chamber is formed 70 therein for the reception of the motor unit, means for securing each of said parts to said motor unit at one end, means disposed in said chamber for securing the opposite end of one of said parts to said motor unit, means accessible from the ex-

terior of said case for securing the opposite end of the other part to the motor unit, shields overlying said matching edge portions to prevent the entrance of foreign matter to said motor chamber, and means disposed at opposite ends of said case for securing said shields in position.

2. In combination, a housing for a motor unit comprising two separable parts, each of said parts having spaced edge portions, the edge portions of one part being shaped to substantially match the edge portions of the other part, each of said parts being formed with a recess so that in the assembled position of the parts a chamber is formed in said housing for the reception of said motor unit, means for securing said parts to said motor unit, shields overlying said matching edge portions, each of said shields being formed in two portions, one of said portions being enlarged and the other of said portions being relatively narrow, each of said enlarged portions having a bracket secured to the inner side thereof, clips secured to opposite sides of said housing shaped to interfit with said brackets to secure the enlarged ends of the shields in position on said housing, said clips being positioned so that the enlarged portions of the shields enclose the clips in the assembled position of the parts, and means for securing the narrow portions of the shields to the housing.

3. In combination, a housing for a motor unit comprising two separable parts, each of said parts having spaced edge portions, the edge portions of one part being shaped to substantially match the edge portions of the other part, each of said parts being formed with a recess so that in the assembled position of the parts to form the housing a chamber is formed therein for the reception of said motor unit, each of said parts being pre-shaped so that on each side of the housing it is formed with shoulders at a first end and an elongated groove extending from one of the shoulders to the opposite end of the housing, said housing having a shoulder formed on each side of the opposite end thereof, means for securing said parts to said motor unit, a shield shaped to overlie the matching edge portions on each side of said housing, said shields being formed in two portions, one of said portions being enlarged and shaped to engage the shoulders formed on the first end of the housing to position the shield and the other of said portions being relatively narrow and being recessed in said groove, said shields and said housing interfitting to form a smooth exterior surface on said housing, said enlarged portion of each shield having a bracket secured thereto, a clip secured to each side of said housing and shaped to interfit with the bracket on each respective shield to positively secure the latter in position, said clips being positioned so that the enlarged portion of each shield encloses the clip in the assembled position of the parts, and each of said narrow portions having an outer end thereof turned back on itself to engage one of the shoulders on the opposite end of the housing to secure the shield thereto.

4. In combination, a housing for a motor unit comprising two separable parts, each having spaced edge portions, the edge portions of one part being shaped to substantially match the edge portions of the other part, each of said parts being formed with a recess so that in the assembled position of the parts a chamber is formed in said housing for the reception of said motor unit, clips on opposite sides of said housing, first screws 10 extending through said clips and said parts and threaded into said motor unit to secure the parts to the motor unit, a second screw at the opposite end of said housing passing through said motor unit and threaded into one of the parts, said screw being accessible when the other of said parts is removed, a third screw accessible from the exterior of the housing passing through the other of said parts at the opposite end of the housing and threaded into said motor unit to 15 secure the respective parts in a tightly assembled relation, a shield overlying said matching edge portions, said shield being formed in two portions, one of said portions being enlarged and shaped to cover said clips and associated screws and the other portion being relatively narrow and being recessed on said housing to form a smooth exterior thereon, said clip having an outwardly extending portion spaced from the housing, said enlarged portion of the shield having a bracket 20 formed thereon interfitting with said outwardly extending portion of the clip to secure the enlarged portion of the shield in position, and means for securing the opposite end of the shield to the housing.
5. In combination, a case for a motor unit comprising two separable parts each having spaced edge portions, the edge portions of one part being shaped to substantially match the edge portions of the other part when the parts are 25 positioned to form a unitary case, each of said parts being formed with a recess so that when the parts are assembled a chamber is formed therein for the reception of the motor unit, means for securing each of said parts to said motor unit at one end, means disposed in said chamber for 30 securing the opposite end of one of said parts to said motor unit, means accessible from the exterior of said housing for securing the opposite end of the other part to the motor unit, and shield means shaped to overlie said matching edge portions to prevent the entrance of foreign matter 35 to said motor chamber.
